ABSORPTION REFRIGERATING APPARATUS

Wulff Berzelius Normelli, Berlin-Charlottenburg,
GermanyApplication December 22, 1932, Serial No. 648,501
In Germany December 23, 1931

5 Claims. (Cl. 62—118)

My invention relates to absorption refrigerating apparatus, and more particularly to apparatus of the intermittent type in which a solid absorbent is employed which forms a chemical compound with the refrigerant.

In apparatus of the above character care should be taken not to increase the generating temperatures to an undue value, since otherwise the refrigerant, for instance ammonia, is liable to decompose. Since the normal generating temperature in air-cooled apparatus must be considerably higher than that in water-cooled apparatus, the generating temperature in air-cooled apparatus attains such a value as to cause a decomposition of the refrigerant, particularly when employing certain chemical absorbents. Apart from these drawbacks which result during the heating period even at normal generating temperatures, it may happen that considerable increases in temperature occur in the generator-absorber upon failure of the automatic control devices which energize and deenergize the heating element of the generator. In this case the heating element may under circumstances remain continuously energized, thus causing not only a very rapid increase in temperature, but also an undue increase in pressure in the apparatus, besides the danger of decomposition of the refrigerant and the melting of the solid absorbent.

The above-mentioned drawbacks are removed according to the invention by very simple means. An object of my invention is to arrange the generator-absorber cooling surfaces which dissipate the heat of absorption to the atmosphere in such a manner as to insure a cooling by air also during the heating period. By such an arrangement an apparatus is obtained in which no valves or flaps are necessary for controlling the flow of the cooling means and in which, furthermore, the temperature does not exceed a predetermined value even in the case of the heating element remaining continuously energized, since the direct air-cooling during the heating prevents the temperature from exceeding a predetermined value.

Another object of my invention is to prevent the decomposition of the refrigerant at increased generating temperatures. This may be accomplished by providing a coating on the inner surfaces of the generator-absorber consisting of an iron tank. Consequently, it is possible to attain higher generating temperatures than has hitherto been the case as well as to employ in the apparatus such absorbents as, for instance, zinc chloride, calcium bromide or strontium bromide, which require in connection with air-cooling a

considerably higher generating temperature than the hitherto usually employed substances, such as calcium chlorid and strontium chlorid. Consequently, in this case such binary compounds may be employed in the absorption refrigerating apparatus of the intermittent type which require for the condensation of the refrigerant at a temperature of 40 degrees centigrade a theoretical generating temperature which lies, at least for one of the compounds which with the refrigerant forms the absorbent, above 120 degrees centigrade. The generator-absorber may be constructed in different ways. For instance, the inner walls of the generator and the surface of the heat-conducting elements may be provided with an enamel coating. Furthermore, the entire inner surface may be metallized by dipping it, for instance, into a lead bath or the like, or the surface may, for instance, be copper-plated. The surface may be also treated with graphite or similar substances, if desired by mixing therewith fluid binding agents which are fired. Also the treatment of the metallic inner surfaces with potassium ferrocyanide may be of advantage.

Another object of the invention is to add to the solid chemical absorbents other substances which remove the water present in the apparatus and thereby prevent damages that might occur at high generating temperatures by the presence of water. For this purpose such admixtures are preferably employed which form a chemical compound with the water taken up by the filling material in the generator. The quantity of the admixtures is preferably so chosen that the filling mass after the generator-absorber has been charged therewith and after all the water taken up during the preparation of the generator has been chemically combined with the admixtures contains still an excess of the admixtures. As admixture, for instance, calcium oxide, strontium oxide, barium oxide or sodium oxide may be employed. Another agent very suitable for this purpose is, for instance, aluminum nitride. The latter forms together with water ammonia and aluminum hydroxide. These final products have no detrimental effect in the apparatus, for the ammonia continues to act as refrigerant in the apparatus, whereas aluminum hydroxide is a solid substance highly resistant to fusion which remains firmly embedded in the absorbing mass.

As the refrigerant, ammonia is particularly advantageous, but also ethylamine and higher amines may be employed.

Other objects will become apparent from the

following specification set forth in reference to the accompanying drawings in which,—

Fig. 1 shows a longitudinal sectional view of a refrigerator for domestic purposes equipped with 5 a direct-air-cooled absorption refrigerating apparatus of the intermittent type;

Fig. 2 shows a horizontal sectional view thereof;

Fig. 3 shows a longitudinal sectional view of an 10 absorber-generator embodying my invention;

Fig. 4 shows diagrammatically another embodiment of my invention in which an absorption refrigerating machine operating with indirect air cooling is located in a refrigerator;

15 Fig. 5 shows an apparatus in which special means are provided for insulating the absorber-generator during the heating period.

Referring to Fig. 1, 1 denotes the absorber-generator located in the upper part of the refrigerator, said absorber-generator consisting of two vessels heated during the generating period by means of heating elements 2 which are connected to the supply circuit through clock switch 18.

Both absorber-generator vessels are charged 25 with strontium bromide saturated with an operating medium; for instance, ammonia. During the generating period the operating medium passes through the branch 3 and a conduit 4 into the condenser 5 consisting of a number of elements provided with cooling ribs, where it is liquefied and then to the intermediate vessel 7 through a conduit 6. The latter is insulated from the cooling chamber 8 by means of a particular insulating medium 9 so as to prevent a heating of 30 the cooling chamber during the condensation. As insulating medium a material with low specific heat, for instance, aluminum foil is particularly suitable for this purpose. The cooling chamber 8 itself is insulated from the surrounding atmosphere by various layers 10 of cork. The intermediate vessel 7 is connected to an evaporator coil 13 through a conduit 11 and 12. The evaporator coil is located in a brine container 14 which serves as cold storage tank. The 35 brine takes up during the evaporation of the refrigerating medium a portion of the cold resulting from the evaporation of the refrigerant and gives it up to the cooling chamber during the generating period. The cold storage tank 14 is preferably charged with liquid having a freezing point between 0° and -10° centigrade; for instance, aqueous glycerine solution which may be mixed with alcohol. The evaporator coil 13 is arranged close to the walls of an ice container 40 15 for freezing ice cubes located in the cold storage tank 14. The lower portion of the evaporator coil communicates with a conduit 17 which serves to charge the apparatus.

Another cold storage tank 16 is secured to the 45 bottom of the storage tank 14. The latter contains a liquid, for instance, water, nitrobenzene or the like whose freezing point is higher than the freezing point of the liquid contained in the upper storage tank 14. In this manner it is possible to equalize within wide limits even in the 50 case of high chamber temperatures the variations of temperature in the cooling chamber which may occur during the heating period as a result of the transfer of heat. The absorber-generator 1 and the condenser 5 are so arranged as to be directly cooled by the air passing along the same.

It may happen that undue increases in pressure in the system occur, in case the heating should be continuously switched in for any reason whatever; for instance, owing to a failure of 55

the clock switch and if a fuse which is provided for controlling the temperature of the absorber-generator to prevent an overheating should fail.

To avoid this danger the intermediate tank 7 in which the refrigerant is collected during the generating period is so dimensioned as to take up the total refrigerant condensed during the normal operation and the condenser 5 is so dimensioned as to take up the excess of refrigerant in the case of danger so that a large free space of 10 condensation is left so as not to cause undue increases in pressure in the apparatus.

It is advisable to construct the intermediate vessel 7 in such a manner that a gas space is left free above the liquid level in normal operation, 15 said space being so large that the vaporous refrigerant leaves the intermediate vessel in a dry state during the absorption period.

The absorber-generator container shown in Fig. 3 consists of a cylindrical jacket 21 and an 20 eccentrically arranged inner jacket 22, the cambered plate covers 23, 24 being welded to the outer jackets so as to form a completely closed vessel. The inner jacket 22 serves for the reception of the heating element. The cover 24 25 is provided with a branch 25 to which a gas conduit is connected leading to a condenser (not shown). 26 is a thermometer pocket projecting into the interior of the absorber-generator. The inner space 27 of the absorber-generator is filled 30 with strontium bromide. In order to prevent decompositions of the refrigerant in the absorber-generator, the inner walls of the absorber-generator, which come in contact with the refrigerant are provided with an enamel coating 35 28. Such a coating is also provided on the metallic surface of heat conducting walls in case the latter are disposed in the absorber-generator for improving the conduction of heat.

In the embodiment shown in Fig. 4, the auxiliary liquid is displaced during the generating period by the heat exchange surfaces of the solid absorbent. 201 is the absorber-generator which may be heated by a coil disposed within a heating pipe 202. The absorber-generator is 45 connected to the condenser 205 through a conduit 204.

The condenser 205 is arranged in a tank 206 which is preferably charged with a solid material to be molten between 40° and 60° centigrade. Sodium phosphate with water of crystallization or another product requiring a great number of calories for melting and a suitable melting point of about 40° to 60° centigrade may be employed. The condenser 205 is through a 50 conduit 207 connected to the storage tank 208 which in turn communicates with the evaporator coil 210. To the lower end of the evaporator coil 210, a conduit 212 is connected to remove the air and water from the apparatus. The evaporator coil 210 is arranged in a cold storage tank 218 disposed in the storage chamber 209. The cold storage tank 218 is provided with an opening for the introduction of a container 219a for freezing ice cubes. The evaporator coil 210 is 55 disposed close to the walls of the container 219a.

The absorber-generator 201 is surrounded by a cooling jacket 203. 216 is a container for the auxiliary liquid. During the absorption period the auxiliary liquid circulates through the conduits 214 and 215. The auxiliary liquid container 216 is arranged in the container 206 in such a manner that the heat which escapes during the absorption from the absorber-generator by means of the circulation of the auxiliary me- 75

dium may be partly given up to the salt contained in the container 206. The container 206 is partly arranged in a tank 213 filled with water and whose upper wall 217 consists of porous clay. It is lined inside with a sheet copper 218. In order to ensure a good transfer of heat from the heating pipe to the absorber-generator a corrugated body 222 surrounds the heating pipe, said body being thermally connected to the inner walls of the absorber-generator.

As soon as the refrigerating apparatus upon closure of the circuit of the coil disposed in the heating pipe 202 is put into operation, the absorber-generator is heated. At the same time the water which at first fills up completely the cooling jacket 203 is also heated. As soon as the temperature rises about 100° centigrade a slight vapor pressure results in the cooling jacket 203 and the water contained in the cooling jacket 203 is forced into the container 216 through the conduit 214. The conduit 215 enters in the upper part of the cooling jacket 203 at such a point that the circulation of the auxiliary liquid between the cooling jacket 203 and the container 216 will already be interrupted at the beginning of the generating period as a result of the development of vapor. If the greatest portion of the water is forced from the cooling jacket 203 into the vessel 216, a state of equilibrium will be established, since now the walls of the cooling jacket 203 which are relatively poorly insulated from the surrounding air carry off the same amount of heat which the water takes up from the heating pipe 202 as a result of its reduced contact surface. The pressure in the cooling jacket cannot, therefore, continue to increase.

The volume of the water in the cooling jacket 203 is small in proportion to the volume of the tank so that no appreciable variation of the water level in the vessel 216 takes place on removing the water from the cooling jacket. The apparatus is also protected from the danger of being overheated.

If owing to a fault the excess in vapor pressure prevailing in the cooling chamber 203 overcomes the counterpressure of the liquid column which exists between the level of the water left in the cooling jacket 203 and the water level in the vessel 216, vapor issues from the tank 214 through the conduit 215, so that now the pressure in the vessel 203 decreases and, consequently, water flows back into the cooling jacket through the conduit 214. The water level in the cooling jacket rises, consequently, again and owing to the heating surface thus increased, a more effective evaporation results so that also in this case a state of equilibrium is established.

At the end of the generating period the excess in pressure in the cooling jacket 203 drops rapidly below the atmospheric pressure so that the cooling jacket 203 fills up with water. The water is heated and circulates between the cooling jacket 203 and the storage tank 216 through the conduits 214 and 215.

Owing to the circulation of liquid during the absorption period, the absorber-generator 201 will be cooled down both inside and outside. The heat of absorption is transferred to the tank 216 as a result of the water circulation. This tank gives up partially its heat directly to the surrounding air with the aid of the walls communicating with outside atmosphere and indirectly to the water contained in the tank 213. The heat which the liquid contained in the tank 213 has

taken up is partly carried off from the walls of the container to the surrounding air.

A further portion of heat is given up in that the clay cylinder 217 absorbs water which vaporizes to the air surrounding the cylinder 217. The heat of vaporization cools the cylinder 217 which transfers this cooling action to the water in the container 213.

The hot water contained in the tank 213 may be tapped by means of a water cock 220 for domestic purposes. The hot water is replaced again by cold water which subsequently fills the tank 213 through the water conduit 226 by means of an automatically actuated level responsive device 225 upon dropping below a predetermined liquid level in the tank 213. The heat of condensation is taken up by the salt mass contained in the tank 206, which heat is partly given up to the surrounding air with the aid of the water contained in the tanks 213 and 216 and partly with the aid of the walls of the tank 206 in contact with the air. The surface of the tank 206 communicating directly with the surrounding air is so dimensioned that the surface itself is sufficient to carry off the heat of condensation even if the tanks 213 and 216 for any reason whatever should be empty. A dangerous increase in pressure in the condenser 205 cannot, consequently, occur. Further, the parts of the tank 213 which give up heat are so dimensioned that they suffice to carry off the heat taken up without the necessity of tapping warm water and of a corresponding supply of cold water.

By cooling the absorber-generator 201, the latter acquires again its absorptive properties and the liquid ammonia contained in the heat insulated storage tank 208 is evaporated with the consequent absorption of heat. The heat of evaporation required for this purpose is abstracted by the evaporator coil 210 partly from the glycerine solution which freezes and partly from the walls of the container for freezing artificial cubes. The frozen glycerine solution cools the cooling chamber 209 by means of the walls of the container 219. The temperature of the cooling chamber is kept constant, since the thermal capacity of the cold storage tank 219 is such that the frozen glycerine solution contained therein will not melt completely during the generating period. In Fig. 4, 227 denotes the clock switch adapted to limit the heating period. The clock switch is connected to the supply circuit (not shown) through the conductors 229, 230. The conductors 231 and 232 lead to the heating coil 218. A safety switch 228 controlled by the float 225 interrupts the heating circuit as soon as the liquid level in the vessel 213 has lowered to an undue amount.

In the refrigerator shown in Fig. 4, a number of possibilities for carrying off the heat of absorption and of condensation to the surrounding air are disclosed. As will be apparent from Fig. 4, the heat of absorption may be given up directly to the surrounding air by means of the circulating auxiliary liquid. A second possibility consists in transferring the heat of absorption from the auxiliary liquid to the water contained in the tank 213 and thence to the surrounding air by means of the walls of the tank 213. It is also possible to dissipate the heat of absorption directly to the surrounding air or to the auxiliary liquid contained in the tank 213 and from the latter to the surrounding air with the aid of a special heat storage tank containing a medium which melts on taking up heat.

In a similar manner, the heat of absorption may be also given up with the aid of the heat storage tank directly to the surrounding air or to a particular auxiliary liquid and from the latter to the surrounding air. For carrying off the heat to the surrounding air either heat conducting walls of the liquid vessel may be used in all these cases or special means may be provided which ensure the dissipation of heat by vaporization of the liquid. Finally, it is also possible to carry off the waste heat after having been stored up by the supply of hot water. In this case the accumulator vessel may be totally or partly insulated and provided with devices which cause upon the attainment of the maximum temperature of the water a further dissipation of heat to the air. These means shown in combination in Fig. 4 may be employed singly or also in any combination whatever for dissipating the heat.

The above-described utilization of the heat of absorption for domestic purposes is particularly of advantage in such apparatus operating with strontium bromide as absorbent. In the case of calcium chlorid mostly hitherto employed in apparatus of the intermittent type, the temperature of warm water attainable is limited to about 45° centigrade, if it is desired to produce a sufficiently low temperature of evaporation. It is possible by the use of strontium bromide to produce hot water of a considerably higher temperature. One may reckon, for instance, with a temperature of 70° to 80° centigrade. In this manner, the waste heat of the apparatus of the intermittent type may be employed far better for various domestic purposes than has heretofore been the case. The hot water may, consequently, be also used for rinsing dishes. Further, it is also possible to utilize the heat of absorption for the production of hot air which serves to dry or heat a dry chamber which, for instance, may be arranged in the refrigerator. In the embodiment shown in Fig. 5, the absorber-generator is designated by the numeral 101 which, for instance, is filled with zinc chlorid saturated with ammonia. The absorber-generator 101 is heated during the generating period by means of a heating element 102 which may be connected to a supply circuit (not shown) through a clock switch 114. By applying heat, the ammonia is driven out of the absorber-generator. The ammonia vapors pass through a conduit 103 into a condenser 104. 151 is a corrugated jacket on which the condenser 104 is wound. The whole body thus prepared is immersed into a metallic bath in order to establish a good heat conduction. 109 is an outer jacket closed at the top thereof, surrounding an absorber-generator. The heat of condensation is carried off by means of the air flowing upwardly in the condenser 104 as a result of the heating so that the refrigerant will be liquefied. The latter passes from the condenser 104 into an intermediate tank 105 embedded in the insulation of the refrigerator, said tank 105 being connected to an evaporator coil 106. The latter is placed in a cold storage tank 133 arranged in the cooling chamber 108. 107 is a container for freezing artificial cubes. 110 are heat-conducting corrugated walls which are disposed between the heating element 102 and the inner walls of the absorber-generator 101. By means of the walls 110, the heat is transferred to the solid absorbents during the generating period. They form cooling ducts which pass through the inside of the generator. The outer walls of the absorber-generator 101 are also provided with heat conduct-

ing walls 111 of the corrugated type so as to form cooling ducts. The heat conducting walls are brought in a good heat-exchange relation with one another when preparing the absorber-generator ready to be built into the apparatus by dipping them into a zinc bath. To the inner cooling ducts at the lower end thereof, an air duct 112 is connected in which a motor-driven ventilator 113 is arranged. The latter is secured by means of bolts 116 so that it may be easily replaced.

The cooling device for the absorber-generator operates as follows. During the generating period the ventilator 113 is deenergized so that it cannot produce a current of cold air. The air heated by the heat radiating parts of the absorber-generator 101 flows upwardly and cannot escape, since the jacket 109 is not provided with an opening at the upper part thereof so that during this period a damming up of the air takes place. Since the jacket 109 consists preferably of heat insulating material, the loss due to heat during the generating period in this arrangement is considerably reduced. The condenser is cooled down directly during this time by the surrounding atmosphere. The condenser operates in a proper manner, since in this arrangement one is not dependent upon a current of cold air caused by a ventilator. Furthermore, the volume of the intermediate vessel 105 and the condenser 104 taken together is so great that the total amount of liquid refrigerant fills up said vessels only to such an extent in case of failure of the clock switch and of the safety device that a free condensation surface is left. In this manner dangerous rises in temperature in the apparatus are prevented.

At the end of the generating period the heating element 102 is deenergized by the clock switch 114 and the ventilator 113 is in turn put into operation which forces the cold air through the cooling ducts of the absorber-generator in the direction shown by the arrows. The cooling air passes at first into the cooling ducts extending inside the generator through the conduit 112 and thence in counterflow to the cooling ducts arranged on the outer periphery of the generator. This current of air is of particular advantage, since the cold air is directed to the hottest parts disposed inside the absorber-generator which, besides, have smaller cooling surfaces, whereas the parts of the absorber-generator which possess more cooling surfaces come into contact with the already preheated cooling air.

115 is a thermostat disposed in the cooling chamber 108, which deenergizes the heating device, for instance, the heating element 102 and the cooling device (ventilator 113) of the absorber-generator in case the temperature of the cooling chamber drops below a predetermined value so that on the one hand, a heating period is shortened or, if desired, even completely omitted and, on the other hand, the production of cold is throttled. The thermostat 115 may also be arranged in the cold storage tank 133. A thermostat 132 is in heat exchange with the absorber-generator 101, said thermostat interrupting the circuit for the heating element 101 in case a predetermined maximum temperature is exceeded. It might also be so connected as to operate the ventilator.

I claim as my invention:—

1. A filling material for the generator-absorber of a refrigerating apparatus operating with solid absorbents consisting of a solid absorbent which

75

is mixed with an oxide of an alkali to remove the water taken up by the solid absorbent.

2. A filling material for the generator-absorber of a refrigerating apparatus operating with solid absorbents consisting of a solid absorbent which is mixed with oxide of calcium to remove the water taken up by the solid absorbent.

3. A filling material for the generator-absorber of a refrigerating apparatus operating with solid absorbents consisting of a solid absorbent which is mixed with oxide of strontium to remove the water taken up by the solid absorbent.

4. A filling material for the generator-absorber of a refrigerating apparatus operating with solid absorbents consisting of a solid absorbent which is mixed with oxide of barium to remove the water taken up by the solid absorbent.

5. In an air-cooled refrigerating apparatus of the intermittent type designed to cool a cooling chamber, said refrigerating apparatus comprising a generator-absorber consisting of an outer cylindrical jacket and an inner concentrically arranged heating tube, an air-cooled condenser, a collecting tank for the reception of the liquid

refrigerant driven off, a valveless refrigerant conduit between said generator-absorber and said collecting tank, the condenser being arranged in said conduit, a heating element for said generator-absorber located in said inner tube, an insulating material surrounding said collecting tank so as to protect the tank against the cooling chamber air and the outside air, the walls of said outer jacket of the generator-absorber being so arranged that the latter is exposed to the cooling influence of the air coming into contact with the outer surfaces thereof during the absorption as well as during the heating period, said collecting tank being so dimensioned as to take up the refrigerant driven off under normal operating conditions and said air-cooled condenser being so dimensioned as to condense the quantity of operating medium driven off when the heating element of the generator-absorber is continuously energized and to take up the excess of condensate without giving rise to undue increases in pressure.

WULFF BERZELIUS NORMELLI.
